END CAP BLANK FOR A SHIPPING PACKAGE

Lewis D. Poggiali, Owosso, Mich., assignor to
Olinkraft, Inc., West Monroe, La.

Filed Mar. 11, 1974, Ser. No. 449,923

Term of patent 14 years

Int. Cl. D9—03

U.S. Cl. D9—245

FIG. 1

FIG. 1 is a top plan view of an end cap blank for a shipping package or similar article embodying my new design.

The end cap blank is of conventional thickness and the dash lines represent fold lines. The bottom is substantially a mirror image of the top shown.

I claim:

The ornamental design for an end cap blank for a shipping package, substantially as shown and described.
